H. H. MERCER

LUBRICATOR

Original Filed June 27, 1918

Patented July 8, 1924.

1,500,599

UNITED STATES PATENT OFFICE.

HENRY H. MERCER, OF CLAREMONT, NEW HAMPSHIRE, ASSIGNOR TO SULLIVAN MACHINERY COMPANY, A CORPORATION OF MASSACHUSETTS.

LUBRICATOR.

Application filed June 27, 1918, Serial No. 242,261. Renewed December 22, 1923.

To all whom it may concern:

Be it known that I, HENRY H. MERCER, a citizen of the United States, residing at Claremont, in the county of Sullivan and State of New Hampshire, have invented certain new and useful Improvements in Lubricators, of which the following is a full, clear, and exact specification.

This invention relates to mechanisms for lubricating and maintaining at a relatively low temperature cooperating parts.

An object of this invention is to provide improved lubricating and cooling means especially adapted for, although not necessarily limited to, the purpose of automatically supplying the necessary lubricant to and preventing overheating of the various working parts of the pneumatic cushioning and power transmission devices employed in certain types of stone working machines. In the operation of such devices it has been found that the parts in a relatively short time become highly heated due to friction and the compressive action of the parts and the supply of lubricant alone even in substantial quantities has not been found universally sufficient to wholly prevent excessive temperatures. Accordingly, the object of this invention is not only the provision of means for successfully and economically supplying a lubricant to such a device, but also the provision of means for maintaining a constant circulation of air throughout the entire device with the object of absorbing and carrying away any excessive heat. Other objects and advantages of this invention will hereinafter more fully appear.

In the accompanying drawings I have shown for purposes of illustration one form which my invention may assume in practice.

In said drawings,—

Fig. 1 is a side elevation of a channeling machine constructed in accordance with the invention.

Fig. 2 is an enlarged detail vertical section taken substantially on the line 2—2, Fig. 1.

Fig. 3 is a still further enlarged elevation of the lubricant receptacle.

Fig. 4 is a section on the line 4—4, Fig. 3.

For convenience, the invention is herein illustrated as embodied in a stone channeling machine which, except as hereinafter pointed out, may be of any usual or well known construction. As shown, said ma-

chine comprises a truck 10 mounted on wheels 11 adapted to run on the usual track-way, said truck having a longitudinally extending trunnion bar 13 on which is adjustably mounted a standard 14, said standard being retained in adjusted position by means of one or more inclined braces 15, as is usual in machines of this character. The standard 14 is provided with suitable vertical guides 16 in which is mounted a sliding frame 17 carrying the cutting mechanism, said sliding frame being vertically adjustable in said guides, to move the cutting mechanism toward and from the work, by means of suitable feeding mechanism 18 which forms no portion of the present invention, and which, being usual in machines of this character, is not illustrated herein. The sliding frame 17 is provided with vertical guides 20 in which is slidably mounted a crosshead 21 carrying a gang of channeling tools 22. The parts thus far referred to, being usual in machines of this general type, require no further description in detail.

The crosshead 21 and tools 22 are reciprocated through suitable connections from a crank shaft 23 actuated by the usual motor, not shown. The connections between the crank shaft 23 and crosshead 21 are such as to provide an elastic yielding medium between said parts, and to convert the rotary motion of said crank shaft into a movement of the tools which will cause them to perform their cutting functions in the most efficient manner. As herein shown, the crosshead 21 is connected to a piston rod 30 secured to a piston 31 working in a cylinder 32 which is mounted for reciprocation in the sliding frame 17, the latter for that purpose having secured thereto suitable guides 33 which receive suitable slides 34 carried by the upper cylinder head 36.

While the cylinder may be of any suitable construction, it is preferably provided with upper and lower heads 36 and 37 between which is interposed the cylinder shell, said heads being united by a plurality of tie rods 38. This construction provides a very light, but exceedingly strong, cylinder, which is also inexpensive to manufacture. The piston rod 30 passes through the lower cylinder head 37, which may be provided with a suitable wearing bushing 39 and a suitable gland or stuffing box 40. The up-

per cylinder head 36 is formed with a tubular extension 45 containing a split bushing 46 in which is guided a piston rod extension 47 projecting upwardly from the piston 31. 5 The upper end of the extension 45 is preferably closed by a tubular cap 48.

Any suitable mechanism may be employed to reciprocate the cylinder 32 from the crank shaft 23 and thereby, through its described connection with the tool carrying crosshead, reciprocate the latter and impart working strokes to the tools, but, as herein shown, the lower cylinder head 37 is provided with wrist pins 41 on opposite sides thereof, said wrist pins being connected by rods or pitmen 42 with said crank shaft. By connecting the pitmen to the lower cylinder head, a structure is provided which is exceedingly light, yet strong, it being apparent that the lifting action is absorbed by an air cushion acting upon the lower head of the cylinder which is directly supported by the connecting rods, while the blow striking force is imparted to the tool by an air cushion whose reaction during downward movement of the cylinder is upon the upper head which is connected by the tie rods 38 to the lower head. For lubricating the wrist pins the cylinder head 37 is provided with an oil chamber 43, the wrist pins 41 being formed hollow and communicating with said chamber, and being further provided with ports 44 leading from their hollow interiors to the exterior surfaces thereof. 35 The wall of the cylinder 32 is provided intermediate its ends with a pair of longitudinally spaced ports 49 and 50 connected by a longitudinally extending bypass passage 51. The lower cylinder head 37 is provided with one or more inlet ports 52 controlled by an inwardly opening spring pressed check valve 53. The bushing 46 is provided with one or more longitudinally extending grooves 54 connecting the upper end of the cylinder with the interior of the cap 48, the latter being provided at its top with a small outlet port 55.

By reason of the bypass 51, the reciprocation of the cylinder 32 is caused to produce an extremely effective cutting action of the tool upon the rock without material reaction upon said cylinder and the other parts of the mechanism. When the piston 31 occupies a position adjacent either end of the cylinder beyond the end of the bypass 51, the air is trapped in that end of the cylinder, causing a sudden impulse to be given to the piston; but when said piston occupies a position between the ports 49 and 50, it is in effect operatively disconnected from the cylinder and free to move upwardly or downwardly under the influence of its initial impulse. The effect is that of throwing the tool forwardly against the rock with great force, releasing the same at

its moment of impact against the rock, and catching the same upon its rebound preparatory to another forward impulse. At each reciprocation of the mechanism a greater or less amount of air passes from the lower end of the cylinder to the upper end thereof through the bypass 51. This loss of air from the lower end of the cylinder is compensated for by the admission of air through the check valve 53 and inlet openings 52, while the excess air at the upper end of the cylinder is gradually discharged through the grooves 54 and outlet opening 55. While, in the operation of the machine, the air will, to a certain extent, surge back and forth through the bypass 51, there is a general tendency, due to the operation of the check valve 53, for the resultant movement of the air to be upwardly from the inlet 52 to the outlet 55. In this manner, an upward flow and renewal of the air in the cylinder are maintained, thereby preventing overheating of the parts due to the compression of the air in the cylinder.

In addition to the openings 49 and 50, the wall of the cylinder 32 is provided intermediate its ends with an opening 56 which is in free communication with the lower portion of a relatively flat lubricant receptacle 57 secured, as by bolts 60, to the exterior of said cylinder wall, and having a top 58 open to the atmosphere. Within the receptacle 57 is a vertical series of curved, downwardly concave baffle plates 59, each of said plates having depending ends extending substantially to the bottom of the receptacle 57. The several baffle plates 59 are disposed in staggered relationship, alternate plates being carried by the inner and outer walls, respectively, of the receptacle 57, and the free edges of adjacent plates overlapping one another. The construction and arrangement of the baffles 59 is such as to facilitate downward flow of liquid in the receptacle 57 while obstructing upward flow thereof.

In operation, the fluid pressure in that portion of the cylinder with which the opening 56 communicates, due to the relative reciprocation of the cylinder and piston 31, fluctuates through a considerable range, being at times less and at other times greater than atmospheric. A current of air is therefore set up in the receptacle 58 and through the opening 56, the direction of said current being at times inward and at other times outward. Said air, due to the baffle plates 59, passes through the receptacle 57 in a zigzag path between the openings 56 and 58. If, therefore, liquid lubricant be supplied to the receptacle 57, said lubricant will tend to gravitate to the bottom of the receptacle 57, a certain quantity of said lubricant passing with the air through the opening 56 into the interior of the cylinder 130

when the flow of said air is inwardly. When, however, air is forced outwardly from the cylinder through the opening 56 and passes upwardly through the receptacle 57, the particles of liquid lubricant carried thereby will impinge upon and be arrested by the baffle plates 59, and will be conducted by the depending ends of said baffle plates back to the lower part of the receptacle. 5 The construction, therefore, provides for a free circulation of air in either direction through the receptacle 57, but comprises means for impeding the upward or outward flow of liquid lubricant in said receptacle, 10 while permitting free downward or inward flow thereof, such downward flow being further assisted by gravity, so that the resultant movement of the lubricant is toward the interior of the cylinder. 15 A portion of the lubricant so reaching the interior of the cylinder 32 will gravitate downwardly therein and reach the piston rod 30 and bushing 39, thereby serving to lubricate the latter parts. Another portion 20 of said lubricant, due to the upward flow of air in the cylinder, as above explained, will be carried upwardly with said air into the grooves or passages 54, thereby lubricating the engaging surfaces of the bushing 46 and 25 piston rod extension 47.

While I have in this application specifically described one form which my invention may assume in practice, it will be understood that this form of the same is shown 30 for purposes of illustration and that the invention may be modified and embodied in various other forms without departing from its spirit or the scope of the appended claims.

40 What I claim as new and desire to secure by Letters Patent is:

1. The combination with a pneumatic device comprising a chamber subjected to fluctuating pneumatic pressures, of means for supplying lubricant to said chamber comprising a lubricant receptacle having free communication with said chamber and provided with means for impeding the flow of lubricant therein in a direction away from 45 said chamber.

2. The combination with a cylinder having a piston therein and a piston rod, of means for supplying lubricant saturated air to the interior of said cylinder, and means 55 for conducting said air along said piston rod to the exterior of said cylinder.

3. The combination with a cylinder, a piston therein having a piston rod extending through both ends of said cylinder and guided thereby, of means for causing a flow of lubricant saturated air longitudinally of 60 said piston rod through one end of said cylinder to the atmosphere.

4. In combination, a chamber subject to 65 fluctuating pneumatic pressure, and a device

for supplying lubricant thereto having communication with the interior of the chamber and with the atmosphere, and adapted to impede the flow of lubricant from the chamber. 70

5. In combination, a chamber subject to fluctuating pneumatic pressures, and a lubricating device therefor having communication with the interior of the chamber and with the atmosphere, and adapted to separate lubricant from air flowing outward through the lubricating device. 75

6. In combination, a chamber subject to fluctuating pneumatic pressures, and an open oil receptacle communicating therewith, provided with baffle means to prevent entrainment of oil with outflowing air. 80

7. The combination with a pneumatic device comprising a chamber subjected to fluctuating pneumatic pressures, of means for supplying lubricant to said chamber comprising a lubricant receptacle open to the exterior of said chamber and having free communication with the interior thereof, said receptacle being provided with means 85 for impeding the flow of lubricant therein in a direction away from said chamber. 90

8. The combination with a pneumatic device comprising a chamber subjected to fluctuating pneumatic pressures, of means for supplying lubricant to said chamber comprising a lubricant receptacle having free communication with said chamber and provided with means for impeding the flow of lubricant therein in a direction away from 100 said chamber while facilitating said flow in a direction toward said chamber. 95

9. The combination with a cylinder and a piston therein, of a lubricant receptacle communicating with the interior of said cylinder, said receptacle being provided with means for impeding the flow of lubricant therethrough in one direction while permitting the flow of gaseous fluid therethrough in either direction. 105 110

10. The combination with a cylinder and a piston therein, of a lubricant receptacle having an opening in its lower portion communicating with the interior of said cylinder, said receptacle being provided with means for impeding the upward flow of lubricant therein while permitting the downward flow thereof to said opening. 115

11. The combination with a cylinder and a piston therein, of a lubricant receptacle having an opening in its lower portion communicating with the interior of said cylinder, said receptacle having a baffle therein adapted to impede the flow of liquid while permitting the free flow of gaseous fluid 120 125 therein.

12. The combination with a cylinder and a piston therein, of a lubricant receptacle having an opening in its lower portion communicating with the interior of said cylinder. 130

inder, said receptacle having a baffle therein adapted to impede the flow of liquid while permitting the free flow of gaseous fluid therein, said baffle having depending ends 5 for directing downwardly liquid impinging against the same.

13. The combination with a cylinder and a piston therein, of a lubricant receptacle having an opening in its lower portion communicating with the interior of said cylinder, said receptacle having a curved, downwardly concave baffle therein, said baffle having depending ends extending substantially to the bottom of said receptacle.

14. The combination with a cylinder and a piston therein, of a lubricant receptacle having an opening in its lower portion communicating with the interior of said cylinder, said receptacle having a plurality of 20 baffles therein arranged in staggered relationship in a vertical series.

15. The combination with a cylinder and a piston therein, of a lubricant receptacle having an opening in its lower portion communicating with the interior of said cylinder, said receptacle having a plurality of 25 baffles therein arranged in staggered relationship in a vertical series, said baffles all having depending ends extending substantially to the bottom of said receptacle.

16. In a stone working machine, in combination, a cutting tool, actuating means therefor, driving connections between said tool and actuating means including a cylinder and a piston therein, and means for supplying lubricant to said cylinder comprising a lubricant receptacle having free communication with the interior of said cylinder and provided with means for impeding the flow 40 of lubricant therein in a direction away from said cylinder.

17. The combination with a cylinder inclined to the horizontal and a piston therein having a piston rod passing through the 45 lower head of said cylinder, of fluid pressure means for supplying lubricant to the interior of said cylinder midway of the length thereof, and means for causing a flow of air from end to end of said cylinder.

18. The combination with an upright cylinder and a piston therein having a piston rod passing through the lower head of said cylinder, of means for supplying lubricant to the interior of said cylinder above the 55 bottom thereof, said means comprising a lubricant receptacle having an opening in its lower portion in free communication with the interior of said cylinder, said receptacle being provided with means for impeding the upward flow of lubricant therein while permitting the downward flow thereof to said opening.

19. In a stone working machine, in combination, a cutting tool, actuating means therefor, driving connections between said

tool and actuating means including a cylinder whose axis makes an angle with the horizontal and a piston therein having a piston rod extending through the lower head of said cylinder, and means for supplying lubricant to the interior of said cylinder above the bottom and below the top thereof. 70

20. The combination with a cylinder and a piston therein having a piston rod extending through one of the heads of said cylinder and a piston rod extension guided in the opposite cylinder head, of means for supplying lubricant to the interior of said cylinder intermediate its ends, said parts having provision for causing said lubricant to flow to said piston rod and piston rod extension. 75

21. The combination with a cylinder and a piston therein having a piston rod extending through one of the heads of said cylinder and a piston rod extension guided in the opposite cylinder head, of means for supplying lubricant to the interior of said cylinder intermediate its ends, said means comprising a lubricant receptacle having free communication with said cylinder and provided with means for impeding the flow of lubricant therein in a direction away from said cylinder, said parts having provision for causing said lubricant to flow to said piston rod and piston rod extension. 80

22. The combination with a cylinder and a piston therein having a piston rod, of a lubricator for supplying lubricant to the interior of said cylinder approximately midway of its length, said cylinder having provision for maintaining a flow of air therein from said lubricator to said piston rod. 100

23. The combination with a cylinder and a piston therein having a piston rod, said cylinder providing a bearing for said piston rod, of a lubricator for supplying lubricant to the interior of said cylinder, said cylinder having provision for maintaining a flow of air therein longitudinally of said piston rod through said bearing. 105

24. The combination with a cylinder inclined to the horizontal and a piston therein having a rod extending through the upper head thereof, of means for supplying lubricant to the interior of said cylinder, said parts having provision for causing an upward flow of air through said cylinder from end to end thereof. 115

25. In combination, a cylinder and a piston therein having a piston rod extension reciprocable through one end of said cylinder, and means for supplying lubricant to the interior of said cylinder, said parts having provision for causing a flow of air along the exterior of said rod extension. 125

26. The combination with an upright cylinder and a piston therein having a rod extending through the upper head thereof, of

means for supplying lubricant to the interior of said cylinder, said cylinder having an inlet opening and an outlet opening at its bottom and top, respectively, and a check valve controlling one of said openings.

27. In combination, a cylinder and a piston therein having a rod extending through one end thereof, and means for supplying lubricant to the interior of said cylinder, 10 said cylinder having an inlet opening at one end thereof and an outlet opening at the other end thereof, a check valve controlling one of said openings, said other opening communicating directly with the atmosphere.

28. The combination with an upright cylinder having an upper head provided with a tubular extension and a piston in said cylinder having a rod extending into said tubular extension, of means for supplying lubricant to the interior of said cylinder, said cylinder having an inlet opening at its bottom, and said tubular extension having an outlet opening at its top, and a check valve 25 controlling one of said openings.

29. The combination with a cylinder having one head provided with a tubular extension, and a piston in said cylinder having an extended rod reciprocable in said tubular extension, of means for lubricating and cooling said parts comprising an opening in the end of said cylinder opposite said extension, and an opening in said tubular extension, and a check valve controlling one of said 35 openings.

30. In a stone working machine, in combination, a cutting tool, actuating means therefor, driving connections between said tool and actuating means including a cylinder and a piston therein having a rod extending through the upper head thereof, means for supplying lubricant to the interior of said cylinder, said cylinder having an inlet opening and an outlet opening in 40 its opposite ends, respectively, and a check valve controlling one of said openings.

31. In a stone working machine, in combination, a cutting tool, actuating means therefor, driving connections between said tool and actuating means including a cylinder and a piston therein having a piston rod, and a lubricator for supplying lubricant to the interior of said cylinder, said 50 connections having means for controlling the relative movement of said cylinder and piston and for maintaining a flow of air in said cylinder from said lubricator to said piston rod.

32. In a stone working machine, in combination, a cutting tool, actuating means

therefor, driving connections between said tool and actuating means including a cylinder and a piston therein having a piston rod and a lubricator for supplying lubricant to the interior of said cylinder, said cylinder having means for maintaining a flow of air therein longitudinally of said piston rod.

33. The combination with a device comprising means forming a chamber having 70 relatively movable walls whereby a fluctuating fluid pressure is produced in said chamber, of means for supplying lubricant to said chamber comprising a lubricant receptacle having free communication with 75 said chamber during periods of relatively low pressure therein, but cut off from communication with said chamber during periods of higher pressure by movement of one of said walls.

34. The combination with a device comprising a cylinder and a piston, said cylinder and piston being reciprocable relative to each other whereby fluctuating pressures are produced at opposite sides of said piston, of means for supplying lubricant to the interior of the cylinder comprising a lubricant receptacle having free communication with the bore of the cylinder at a point so disposed that it communicates with the 90 chambers at the opposite sides of the piston only during the periods when the pressures in said chambers are substantially equal to or below atmospheric.

35. In a machine of the class described, 95 the combination including a cylinder member, a piston member therein, means for positively reciprocating one of said members, means for interconnecting the spaces within the cylinder member at opposite sides 100 of the piston member when said members are in a predetermined relative position, and lubricant supply means communicating with the interior of said cylinder at a point spaced from the ends thereof.

36. In a machine of the class described, the combination including a cylinder member, a piston member therein, means for positively reciprocating one of said members, bypass means for interconnecting the 110 spaces within the cylinder member at opposite sides of the piston member when said members are in a predetermined relative position, and lubricant supply means communicating with the interior of said cylinder 115 at a point between the points of communication with the cylinder bore of said bypass means.

In testimony whereof I affix my signature.
HENRY H. MERCER.
